UNITED STATES PATENT OFFICE.

ROBERT A. CLARK, OF PETROLIA CITY, PENNSYLVANIA.

IMPROVEMENT IN DRILL-ROD COUPLINGS.

Specification forming part of Letters Patent No. 141,694, dated August 12, 1873; application filed February 1, 1873.

To all whom it may concern:

Be it known that I, ROBERT A. CLARK, of Petrolia City, in the county of Butler and State of Pennsylvania, have invented a new and Improved Drill-Rod Coupling, of which the following is a specification:

My invention consists of one section—say, the lower one—having a screw-threaded portion at the end of smaller size than the rod screwing into a socket in the end of the other section by a right-hand screw, and a sleeve screwing on the two sections by a left-hand thread down against a collar on the lower section by which the joints are locked so that it cannot work loose.

Figure 1 is a sectional elevation of my improved joint, and Fig. 2 is a horizontal section taken on the line $\alpha\alpha$ of Fig. 1.

Similar letters of reference indicate corresponding parts.

A represents the lower section of the rod, and B the upper section, to be jointed together. C is a collar on the lower section below the screw-threaded portion D. E is a part of the upper end of the lower section, made small enough to screw into a socket in the lower

end of the upper section B—say, by a right-hand thread. H is a portion of the lower end of the top section of the same size as the part D of the lower section, and correspondingly screw-threaded—say, by a left-hand thread. F is a sleeve, screwing on H and D against the collar C, and so locking the parts of the joint that they bind tightly no matter which way either section of the rod may be turned. The collar prevents the sleeve from screwing down and loosening the joint.

To take it apart, the sleeve is screwed above the point where the parts D and H butt together.

Having thus described my invention, I claim as new and desire to secure by Letters Patent—

The sections A B connected together by a part of one screwing into a socket of the other, and a sleeve on both screwing against a collar on one, the threads being reversed as to the pitch, substantially as specified.

ROBT. A. CLARK.
